UNITED STATES PATENT OFFICE

NAT LITWIN, OF BROOKLYN, NEW YORK

SCREEN-REPAIRING DEVICE

Application filed October 22, 1929. Serial No. 401,576.

This invention relates to screen repairing devices and is particularly directed to a device for repairing punctured wire window screens and the like devices and to the method of making such devices as salable articles of manufacture and to the method of repairing screens by use of such devices.

An object of this invention is to provide a neat, compact and rugged device of the character described which shall be inexpensive and simple to manufacture, easy to apply and positively secure to a punctured or torn screen and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a front elevational view of a window screen with repair devices embodying the invention applied to intermediate and corner portions thereof;

Fig. 2 is a cross-sectional view taken on line 2—2 of Fig. 1;

Fig. 3 is a perspective view of a repair device embodying the invention adapted to be applied to an intermediate portion of the screen;

Fig. 4 is a fragmentary perspective view of a repair device embodying the invention but illustrating a modified construction thereof; and

Fig. 5 is a top plan view of woven screen material illustrating an intermediate step in the manufacture of the repair devices.

Referring now in detail to the drawing, 10 designates a window frame in which is mounted a screen 11 comprising a screen frame 12 and screening material 14 secured thereto as by a molding 30. The screen is illustrated as having an intermediate hole

or puncture 15 and a hole or puncture 16 adjacent one corner thereof. Fig. 3 illustrates a repair device 17 embodying the invention in the form of a patch adapted to be applied to the screening material 14 and attached thereto in the manner hereinafter appearing, over the opening 15 to cover said opening.

The patch device 17 comprises a portion of interwoven wire screening material 18 of rectangular or any other suitable shape. The outer ends of the wires forming the material 18 are formed with portions 19 extending in the plane of the patch and somewhat beyond the end wires 18a transverse thereto. Extending from said portions 19 are outer free end portions 20 bent at substantially right angles to the plane of the patch as clearly illustrated in Fig. 3. A few drops 21 of solder or the like material may be applied adjacent the edges of the patch to bind the wires extending in one direction to the wires extending in the transverse direction. This construction serves to stiffen the patch and prevent distortion of the device as for instance, when the pressure is applied thereto on a bias.

The application of the device 17 to the screen 11 will now be obvious. The patch is merely placed over the opening or perforation 15 in the screen to suitably cover the same, and said patch is then pushed against the screen so that the free end portions 20 will project through the openings in the screen. Said free end portions are preferably then bent outwardly into contact with the opposite side of the screen to firmly secure said patch to the screen.

The upper right hand corner of Fig. 1 shows a patch 17a applied to a corner of the screen, the molding 30 being partially broken away to more clearly disclose the structure. For forming a patch adapted for attachment to the screen adjacent the edge or corner portions thereof, the extensions 19, 20 are preferably severed or cut away from the edge portions of the patch which are adapted to contact the edges of the screen, thus leaving a flat edge portion which is adapted to underlie the molding. Thus the patch 17a is pro-

vided with two flat edge portions 31 and 32 which may be placed under the molding, the other two edge portions of said patch being formed with said projections 19, 20 for attachment to the screen.

In applying the patch 17 to the screen, should two adjacent end portions 20 extend thru a single opening in the screening material, distortion of the patch will be prevented 10 since the portions 19 extending from said adjacent free end portions 20 may bend toward each other upon pressing the patch against said screen.

Fig. 5 illustrates one method of fabricating the patches 17. The screening material shown by full lines in said figure are woven by any suitable method to form the pattern shown comprising rectangular interwoven screen wire portions 18 interconnected and 20 spaced from one another by horizontal wires 35 and vertical wires 36. These parallel wires 35, 36 may then be cut mediate the ends thereof along the dot-dash lines shown in Fig. 5 to form separate pieces from which 25 the free end portions 20 may be bent by any suitable means to form the patches.

In accordance with the modified construction shown in Fig. 4 the looped end portions 37 shown in Fig. 5 and formed in the weaving of the screening material, are not cut to form separate end portions, but are bent at right angles to the plane of the patch 17b. Furthermore said looped portions are preferably bent inwardly as at 38, 39 to form rugged 35 looped legs 40 adapted to project through the screen 14 upon applying the patch to said screen to cover an opening therein, in the manner described above.

It will thus be seen that there is provided a 40 device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawing, is to be interpreted as illustrative and not in a limiting sense.

Having thus described my invention I claim as new and desire to secure by Letters Patent:

1. As an article of manufacture, a device for repairing screens, comprising a patch of woven screen wire, extending looped portions of said woven wire constituting means for attaching said patch to a screen.

2. In combination with a screen, a patch therefor, comprising screening material having looped wire end portions around the perimeter thereof extending at right angles to 65 the plane of said material, and adapted to

project thru the screen openings whereby said patch may be pushed into contact with said screen.

In testimony whereof I affix my signature.
NAT LITWIN.
